UNITED STATES PATENT OFFICE.

PETER DULK, JR., OF ELIZABETH, NEW JERSEY.

METHOD OF MAKING PISTON-RINGS.

1,121,336.

Specification of Letters Patent. Patented Dec. 15, 1914.

No Drawing.

Application filed April 15, 1914. Serial No. 831,924.

To all whom it may concern:

Be it known that I, PETER DULK, Jr., a citizen of the United States, residing in Elizabeth, in the county of Union and State of New Jersey, have invented certain new and useful Improvements in Methods of Making Piston-Rings, of which the following is a full and clear specification.

My invention relates to methods of making piston rings and has for objects, first, to eliminate a number of operations heretofore thought necessary in the manufacture of piston rings, thereby reducing the cost of manufacture and increasing the output of a given equipment; second, to improve the accuracy of the rings and also the quality of the piston rings with respect to their resistance to wear, thereby increasing the life and efficiency of the rings.

My invention and the result accomplished by it will be best understood by reference to some of the known methods of manufacturing piston rings, which comprise substantially the following steps:

1. The rings are usually cut from a long sleeve or cylinder which has previously been bored and reduced on its outer surface to approximately the required thickness, or they can be cast singly with a small allowance for finishing.

2. Each ring is then reduced to approximately the required width by inserting it between oppositely revolving grinding disks.

3. Each ring is then split or cut obliquely at one point and its inside surface is peened, and the bur formed by the first grinding operation is removed with the file. The rings are now required to be reduced to the proper width of working surface, it being understood that the rings are cut from the sleeves or cylinder over size in this respect. The width of the working surface is of extreme importance. This width must be accurate and uniform in each ring and all the rings must be identical within a small margin of error.

4. It then becomes necessary to flatten or straighten the ring since the former operations have resulted in the free ends of the cut or split ring becoming out of alignment.

5. The ring is placed flat against a magnetic chuck and is again reduced in width by means of an emery disk. The importance of the straightening operation (5) will now be seen inasmuch as if the ring did not lie flat against the chuck more material

would be removed from some parts of the ring than from others.

6. The ring is then removed from the chuck and turned over, exposing its other face, and the emery disk is again applied and the ring is reduced to a size permitting only the removal of a small quantity of material for the purpose of finishing the surfaces.

7. Before finishing, however, it becomes necessary to repeat the straightening operation which, it must be understood, is a manual operation, requiring the employment of skill.

8. The ring is then applied to the magnetic chuck for finishing and is ground first on one side, then turned and ground on the other. This time, however, less material is removed.

9. For the second time it becomes necessary to remove the bur formed by the grinding operations. This operation of removing the bur consists in placing the ring on a rapidly revolving cone chuck and then applying the file, first to one edge and then the other of the ring. It will be seen that this is an operation of some danger to the operator's fingers, inasmuch as the ring quickly takes up the movement of the chuck and must be promptly released. Among other advantages which I claim for my invention is the elimination of this second burring operation.

By my invention I propose to eliminate a number of operations by introducing a single operation which performs all the functions of the operations which I have described above number 4 to 9, inclusive. Moreover the single operation which I propose to introduce will take less time and consequently be cheaper than any one of the operations which I am enabled to eliminate.

According to my method, the ring blanks are prepared in the usual way by cutting from the sleeve or cylinder or by any other way and rough ground, split, burred and if desired peened in the usual way. I then take the ring and reduce the working surface to the desired width by applying pressure to the opposite faces of the ring. By this single operation the ring is straightened, reduced to size and the surfaces finished. Furthermore, the rings produced by my method will possess a quality not found in rings of the prior art. As is well known,

piston rings are made usually of cast iron, which is spongy and porous. It is obvious that the wearing qualities of the ring will be improved by compacting the material, whereby it becomes more dense and close in texture.

I have found by experiment that if the rings are first reduced to approximately the required size by means of the first grinding 10 operation described above, I can safely reduce the width of the ring by pressure without seriously affecting its radial thickness.

While I propose to adopt as the means for pressing the rings a power press having 15 parallel die faces, I do not wish to limit myself to this particular pressure device. Without departing from the spirit of my invention I may use pressure rollers or any other suitable means. By using flattening 20 dies of sufficient size I shall be able to press rings of any diameter from the largest to the smallest. Furthermore it is immaterial whether the rings be concentric or eccentric.

One advantage of the method I employ 25 relates to the elimination of the emery disks for performing the final operation of reducing the rings to size. As is well known, grinders of this nature must be kept in constant adjustment for accurate work, in view 30 of the wearing away of the grinding surface. Pressure devices, on the other hand, such as those I have mentioned will maintain their adjustment for a comparatively

long period. Therefore, losses from failure to keep the machinery in adjustment 35 will be less if my method is employed.

I find that by bending the ring to a proper shape, separating its ends after the splitting operation, and then thereafter compressing it the ring will become set with 40 its ends separated, giving the required tension when compressed. I thereby eliminate the operation of peening which has heretofore been one of the methods used for spreading the ends and giving the ring the 45 desired tension.

I claim:

1. In methods of making piston rings, a finishing operation, comprising compressing the ring axially, whereby the working 50 surface is reduced to the desired width, the material of the ring is compacted, and the ring is flattened.

2. The method of making piston rings, which comprises splitting the ring, expanding 55 the ring to separate its ends, and then compressing the ring axially whereby the metal becomes set with the ends separated, and whereby the required tension is imparted to the ring when it is contracted to 60 operative form.

PETER DULK, JR.
